CLAIM

The ornamental design for a cordless phone base station, as shown and described.

DESCRIPTION

FIG. 1 is a top plan view of a cordless phone base station showing our design;

FIG. 2 is a left side elevational view thereof;

FIG. 3 is a right side elevational view thereof;

FIG. 4 is a bottom plan view thereof;

FIG. 5 is a front elevational view thereof;

FIG. 6 is a rear elevational view thereof; and,

FIG. 7 is a top, front and right side perspective view thereof.

The broken line showings throughout the views are for illustrative purposes only and form no part of the claimed design.

FIG. 1

FIG. 2

FIG. 3

FIG. 4

FIG. 5

FIG. 6
